COMBINED LAMP HOUSING AND FILTER
HOLDER FOR ULTRA-VIOLET LAMPS

George C. Smith and Catherine A. Hemsing, Los Angeles, Calif., assignors to Defiance Manufacturing Company, Inc., Los Angeles, Calif., a corporation of California

Application June 16, 1950, Serial No. 10,564

Term of patent 14 years

(Cl. D48—23)

To all whom it may concern:

Be it known that we, George C. Smith and Catherine A. Hemsing, both citizens of the United States of America, both residing at Los Angeles, in the State of California, have invented a new, original, and ornamental Design for a Combined Lamp Housing and Filter Holder for Ultra-Violet Lamps, of which the following is a specification, reference being had to the accompanying drawing, forming a part hereof, in which:

Fig. 1 is a top perspective view of a combined lamp housing and filter holder for ultra-violet lamps, showing our new design;

Fig. 2 is a fragmentary side elevational view thereof;

Fig. 3 is a fragmentary top plan view; and
Fig. 4 is an end elevational view.

We claim:

The ornamental design for a combined lamp housing and filter holder for ultra-violet lamps, as shown.

GEORGE C. SMITH.
CATHERINE A. HEMSING.
